US00D632772S

(12) **United States Design Patent**
Abbondanzio et al.

(10) **Patent No.:** US D632,772 S
(45) **Date of Patent:** ** *Feb. 15, 2011

(54) **AIR FRAGRANCE HOUSING**

(75) Inventors: **Matthew Abbondanzio**, Milwaukee, WI (US); **Glenn Walters**, Port Washington, WI (US); **Megan C. Sorrell**, Milwaukee, WI (US)

(73) Assignee: **S.C. Johnson & Son, Inc.**, Racine, WI (US)

(*) Notice: This patent is subject to a terminal disclaimer.

(**) Term: **14 Years**

(21) Appl. No.: **29/365,541**

(22) Filed: **Jul. 9, 2010**

Related U.S. Application Data

(63) Continuation of application No. 29/346,432, filed on Oct. 30, 2009.

(51) **LOC (9) Cl.** 28-99

(52) **U.S. Cl.** D23/366

(58) **Field of Classification Search** ..... None
See application file for complete search history.

(57) **CLAIM**

The ornamental design for an air fragrance housing, as shown and described.

DESCRIPTION

FIG. 1 is an isometric view of a top, front, and right side of an ornamental design for an air fragrance housing;

FIG. 2 is a front elevational view of the housing of FIG. 1;

FIG. 3 is a rear elevational view of the housing of FIG. 1;

FIG. 4 is a left side elevational view of the housing of FIG. 1;

FIG. 5 is a right side elevational view of the housing of FIG. 1;

FIG. 6 is a top plan view of the housing of FIG. 1;

FIG. 7 is a bottom plan view of the housing of FIG. 1; and, FIG. 8 is a top plan view of an alternative embodiment of the housing of FIG. 1.

The subject matter shown in dashed lines is for illustrative purposes only and forms no part of the claimed invention.

1 Claim, 7 Drawing Sheets
